UNITED STATES PATENT OFFICE.

JOSEPH SZAKÁCS AND SZABO FERENCS, OF CLEVELAND, OHIO.

LIFE-BELT.

1,377,033.

Specification of Letters Patent.

Patented May 3, 1921.

Application filed November 12, 1920. Serial No. 423,524.

To all whom it may concern:

Be it known that we, JOSEPH SZAKÁCS and SZABO FERENCS, citizens of Hungary, residing at Cleveland, in the county of Cuyahoga and State of Ohio, have invented certain new and useful Improvements in Life-Belts, of which the following is a specification.

This invention relates to certain new and useful improvements in life belts and has for one of its objects to provide a life belt embodying a body harness adapted for attachment to a person and securely retained in position by straps carried by the belt.

15 A further object of the invention is to provide a life belt including a circular web portion adapted for positioning upon the body of the wearer with cork floats positioned at the inner and outer edges of the web portion.

20 A still further object of the invention resides in the provision of a life belt embodying an apron formation of web normally lying adjacent the body of the wearer and adapted to be extended outwardly therefrom to a circular horizontal position during operation with buoyant floats positioned at the inner and outer edges of the apron web.

25 With the above and other objects in view, the present invention consists in the novel form, combination and arrangement of parts hereinafter more fully described in connection with the accompanying drawings and in which like reference characters indicate similar parts throughout the several views.

30 In the drawings,—

Figure 1 is a perspective view of a life belt constructed in accordance with the present invention and shown in operative position upon a person,

35 Fig. 2 is a top plan view of the belt showing the radial arms carried by the web portion thereof with buoyant members at the inner and outer ends of the arms,

40 Fig. 3 is a side elevational view of the belt in collapsed form upon the body of the wearer,

45 Fig. 4 is a fragmentary elevational view of the belt showing the lacing connection for the placket of the apron and draw string associated with the inner ends of the float arms,

Fig. 5 is a cross sectional view taken on line V—V of Fig. 1 showing the float arm attached to the apron web and

55

Fig. 6 is a perspective view of one of the float arms.

Referring more in detail to the accompanying drawings, there is illustrated a life belt including a circular apron web 1 of waterproof material having a V-shaped placket section 2 with which a lacing cord 3 is associated for closing the placket in mounting the apron belt upon the body of the wearer. Crossed shoulder straps 4 shown in Figs. 1 and 3 are attached to the upper end of the apron 1 for holding the apron section correctly positioned beneath the arms of the wearer as shown in said figures. Belt sections 5 are associated with the placket opening 2 and are adapted for engagement with the buttons 6 at opposite sides of the placket opening to insure the proper mounting of the belt upon the body of the wearer.

70 The apron section 1 at its upper end is of a circumferential length to snugly engage the body while the lower circumference is of increased length as shown in Figs. 1 to 3 to permit the apron section 1 to be moved outwardly to a buoyant horizontal position as shown in said figures to assume a horizontal position when in operation. Float arms are associated with the apron section 1 and include wooden arms 7 having a flexible waterproof covering 8 securing the arms to the apron section 1 as at

75 9 as clearly shown in Fig. 5. A cork or other buoyant ball member 10 is carried by the outer end of each arm while a similar

90 block 11 is carried by the inner end of each arm, thereby providing buoyant floats at points in proximity of the body of the wearer and at the outer edge of the apron section 1. A tie cord 12 having rings 13

95 upon the ends thereof to prevent disengagement of the tie cord with the float arms is loosely passed through slide guides 14 carried by the float blocks 11 and adapted

100 to be drawn to the position shown in Fig. 1 to securely fasten the belt upon the body and to prevent movement of the inner ends of the float arms and apron section 1 relative to the body, the free ends of the tie cord

12 being suitably tied or knotted to hold the float arms in position.

In the operation of the device, the belt is attached to the body of the wearer as shown in Fig. 3, the shoulder straps 4 preventing the belt from sliding downwardly upon the body while the lacing cord 3 for the placket section 2 and the straps 5 bind the apron section 1 around the body of the wearer. The tie cords 12 may be also employed for anchoring the inner ends of the float arms relative to the body so that when the belt is moved to the operative position as shown in Fig. 1 when within water, it will be horizontally positioned with the arms extending radially from the body. The buoyant members 10 and 11 will ride upon the surface of the water with the apron section 1 also insuring the flotation of the belt and person wearing the same.

While there is herein shown and described what is believed to be the preferred embodiment of the invention, it is nevertheless to be understood that minor changes may be made therein without departing from the spirit and scope of the invention as hereinafter claimed.

What is claimed as new is:

30 1. A life belt of the type described comprising an apron section, a closing placket

therefor and radial float arms carried by the apron section.

2. A life belt of the type described comprising an apron section, a closing placket 35 therefor, radial float arms carried by the apron section and a tie cord associated with the inner ends of the float arms to bind the inner ends of the arms to the body of the wearer. 40

3. A life belt of the type described comprising an apron section, a closing placket therefor, radial float arms carried by the apron section, said float arms including a buoyant block at each end thereof. 45

4. A life belt of the type described comprising an apron section, a closing placket therefor, radial float arms carried by the apron section, said float arms including a cork float at each of the ends and a flexible 50 covering for the arms and floats.

5. A life belt of the type described comprising an apron section, a closing placket therefor, radial float arms carried by the apron section, the float arms being secured to 55 the apron section over their entire lengths and a float carried by each end of the arms.

In testimony whereof we affix our signatures.

JOSEPH SZAKÁCS.
SZABO FERENCZ.
